UNITED STATES PATENT OFFICE

2,135,564

WEATHER STRIP AND SASH HOLDER

Peter Delich, Duluth, Minn.

Application March 19, 1937, Serial No. 131,912

1 Claim. (Cl. 292—18)

This invention relates to combined weather strips and sash control means, the principal object being to provide practical means for vertical control of a window sash without the necessity of weights and at the same time produce an adequate weather strip.

Another object is to provide such a device conveniently manipulated by hand to increase or diminish the efficiency of same as a sash control means, particularly to compensate for varied requirements in respect to the weight of the window to which it is applied.

Other objects and advantages of the invention will appear in the following description thereof.

Referring now to the accompanying drawing, forming part of this application, and wherein like reference characters indicate like parts:

Figure 1 is a perspective view of a fragmental portion of the outer edge of the window sash having one embodiment of the invention attached thereto.

Figure 2 is a perspective view of the crank member for adjustment of the device.

Figure 3 is an end view of the two cooperative clamping members in the device.

Figure 4 is a perspective view of a fragmental portion of the weather strip and clamp engaging tongue or bead.

Figure 5 is a somewhat enlarged view of the clamping unit assembled ready for installation.

Figure 6 is a perspective view of the adjusting plug.

Figure 7 is a perspective view of the clamp spring and pintle.

Figure 8 is a transverse sectional view of the clamp member just inwardly of their supporting pintle.

1 represents a portion of a common window sash, however having a groove or channel 2 formed centrally of the jamb engaging face, and, preferably about centrally of the vertical height of the sash is formed an enlargement 3 of the slot providing a pocket for my improved control means and on the face of the sash runway in the 5 jamb is attached in any desired manner the combined weather strip 4 and track, the track portion of the bead being indicated at 5.

The clamping unit is carried within a U-shaped supporting member 6 of flat bar metal having 0 the parallel extensions 7 thereupon in which is installed the clamp supporting pintle 8. The clamping members comprise the body portions 9 and clips 10, each clamping member having approximately centrally thereof a turned in lip indicated at 11 on either edge thereof and which

5 lips are perforated to receive the pin 8. The lips on one of the clamping members (immaterial which) are of less distance apart than the other member so that they fit one within the other as clearly shown in the drawing.

About the pintle 8 and intermediate of the lips or bearings 11 of the smaller member is installed the spring 12, the termini of which are given several turns about the pintle 8 adjacent its ends and then extend outwardly to provide adequate 10 bearing against the inner walls of the body portion 9 of the clamping members to bias them outwardly, which results in the lips 10 of the clamping member being biased inwardly for the purpose of frictionally engaging the bead or tongue 15 5 of the weather strip 4 when engaged thereby.

As adjusting means for these clamping members I have illustrated the interior of the body portion of one of such as being provided with a slight enlargement or hub-like portion 13 having 20 a hole therethrough internally screw threaded for the reception of the bolt 14 which is provided with a flange 15 upon its outermost extremity. From the center of this flange extends the rectangularly shaped projection or head 16 to 25 which the crank 17 may be applied as noted in a selective position as the hole in the crank for such engagement is of the form of a Greek cross permitting of its being applied in various radial positions in respect to the bolt. Obviously the 30 clamping members are installed in the pocket 3 before the bolt 14 is applied thereto, and there is a hole through the innermost wall of the sash 1 for registration with the holes in the body portions of the clamping member. Consequently, 35 after such installation and that of the bolt 14 and of the escutcheon plate 18 mortised within the face of the sash, it having the depressed socket 19 therein sufficiently large to receive the flange 15 of the bolt 14, the latter being sufficiently long to reach to the screw threaded portion of the farthest clamp body portion, when the bolt is screwed in it will tend to draw the body 40 portions of the clamping members together, thus 45 opening the lips 10 of said members to any desired degree depending upon the pressure of the adjusting screw. Thus such frictional contact is designed to fully compensate for the gravitating tendency of the window, and there may be such 50 connections upon one or both sides of each window sash as desired.

To augment the frictional contact of the lips 10 upon the bead 5 of the weather strip I have shown it as being provided with a series of per- 55

forations 20 which is deemed to suffice for such increase of the frictional contact.

If preferred, when these weather strips are made, the perforations may only be formed in one side of the bead 5 to provide against lessening the function of this member as a weather strip.

It is to be understood that various departures from the specific construction shown may be resorted to without departing from the spirit of the invention, and the combination of elements set forth in the appended claim.

Having thus described my invention, what I claim and desire to secure by Letters Patent, is:

A sash control for windows having longitudinal slots in its side edges for cooperation with weather strip elements, said sash control comprising spring biased clamping members pivoted together between their side edges, and carried by 5 the sash and adapted for frictional engagement upon opposite sides of the extending portions of said weather strip elements, and a bolt extending through one of said members and screw threadedly into the other for regulating the force 10 of said spring.

PETER DELICH.
